(57) **CLAIM**

The ornamental design for a flexible track for fabric wall coverings, as shown and described.

DESCRIPTION

FIG. 1 is a perspective view of a flexible track for fabric wall coverings.

FIG. 2 is a front view of the flexible track for fabric wall coverings of FIG. 1.

FIG. 3 is a back view of the flexible track for fabric wall coverings of FIG. 1.

FIG. 4 is top view of the flexible track for fabric wall coverings of FIG. 1.

FIG. 5 is a bottom view of the flexible track for fabric wall coverings of FIG. 1.

FIG. 6 is a first side view of the flexible track for fabric wall coverings of FIG. 1; and,

FIG. 7 is a second side view of the flexible track for fabric wall coverings of FIG. 1.

The flexible track for fabric wall coverings is shown with a symbolic break in its length. The appearance of any portion of the flexible track for fabric wall coverings between the break lines forms no part of the claimed invention.
